UNITED STATES PATENT OFFICE.

GEORGE M. HOLLENBACK, OF LEWISTOWN, MONTANA.

CENTRIFUGAL-PRESSURE CASTING APPARATUS.

1,310,865.

Specification of Letters Patent. Patented July 22, 1919.

Application filed July 11, 1918. Serial No. 244,468.

To all whom it may concern:

Be it known that I, GEORGE M. HOLLENBACK, a citizen of the United States, residing at Lewistown, in the county of Fergus 5 and State of Montana, have invented new and useful Improvements in Centrifugal-Pressure Casting Apparatus, of which the following is a specification.

This invention relates to improvements in 10 centrifugal pressure casting apparatus, and it has for its object to provide improvements of the nature stated, particularly adapted for casting dental inlays, bridges, saddles, and other elements, as well as 15 jewelry structures and other fine forms and elements in which accuracy of conformation and even distribution of the structural mass is highly important. The invention has for its object the provision of improved apparatus of the general character stated which will be superior in point of inexpensiveness and efficiency, taken in conjunction with simplicity, positiveness and effectiveness of 20 operation, facility in control, compactness 25 in form, convenience in adjustment of parts and members to compensate for variations in working conditions, duration or maintenance of operation predicated upon a given amount of motive power, and reliability and 30 accuracy in performance, and which will be generally superior in serviceability and adaptability to varying conditions of service.

With the above and other objects in view, the invention consists in the useful and 35 novel provision, formation, construction, combination, inter-relation, association and mode of operation, as well as adjustment and control of parts, members and features, all as hereinafter described, shown in the 40 drawing, and finally pointed out in claims.

In the drawing:

Figure 1 is a central vertical sectional view of improved apparatus embodying and exemplifying the invention, parts being in 45 elevation;

Fig. 2 is a horizontal detail fragmentary transverse sectional view taken upon the line x^2-x^2 , Fig. 1, and looking in the direction of the appended arrows;

Fig. 3 is a detail transverse sectional view taken upon the line x^3-x^3 , Fig. 1, and looking in the direction of the appended arrows;

Fig. 4 is a side elevation of a crucible entering into the organization shown in 55 Fig. 1, the same being in detached position and upon an enlarged scale;

Fig. 5 is a detail transverse sectional view, taken in a plane at an angle of 90 degrees to that of Fig. 1, and upon the line x^6-x^6 , Fig. 1, parts being left in elevation; and, 60

Fig. 6 is a side elevation of the crucible shown in Fig. 5.

The nether portion of the crucible in Figs. 4 and 6 is broken away slightly for convenience in illustration.

Corresponding parts in all the figures are designated by the same reference characters.

Referring with particularity to the drawing, A designates a crucible with which is adapted to be associated a flask B containing a mold b formed in an investment of initially plastic material, or the like, c, and adapted to be held to an opening 6 in one end of the crucible, by an annular flange 7 upon the wall of the crucible at that end, 75 and within which flange one cylindrical end of the flask fits. C designates means, in accordance with the invention, for holding the flask to the crucible, in proper alinement, and in the relation last stated, such flask and 80 crucible being jointly mounted for rotation upon an arm 8 to which is opposed and alined a counter-balance arm 9, having a shiftable counter-balance 10, said arms 8 and 9 being joined together by a ring 11 85 which is applied exteriorly to a rotatable sleeve 12 having an adjustably threaded point bearing 13, applied rotatably to an upright post 14. The ring 11 is adjustably applied to the sleeve 12, and held thereto, 90 for rotation therewith, by a set screw or thumb screw 15. The upright post 14 is mounted vertically in a base 16, which is vertically chambered or bored, as at 17, to accommodate such post, the latter being firmly 95 held in position at its lower ends by a nut 18 applied to threads thereon and received and accommodated within a bottom chamber 19 in the base 16. Above the chamber 19 is provided a top chamber 20 in the base 16, 100 and within the same is disposed a free hub or annulus 21, surrounding the post 14, and surrounding such annulus 21 is a coil spring, such as a clock spring, 22, comprising means for supplying energy for the rotation of the 105 sleeve 12 and its connected arms 8 and 9. The spring 22 is fast at one end, as at 23, to the hub 21, and at the other end, as at 24, to the base 16. The sleeve 12 is provided with a broad base flange 12^a, which overlies the 110 chamber 20, and carries a dog 25 beneath such flange, as at 25^a, there being secured at

one end at such latter pivotal point a leaf spring 26 the free end of which bears upon the outer end of the dog 25 urging the same into engagement with a notch 27 in the hub 21, to operatively connect such flange 12^a and such hub 21 so that the spring 22, by rotation of the sleeve 12, may be put under compression and its energy stored, or such sleeve 12 may be resultantly rotated by the 10 energy of the spring so stored. The pressure of the spring 26 is such, and is so related to the centrifugal tendency of the dog 25, that after the rotatable carriage including the arms 8 and 9 and sleeve 12 have been 15 brought up to their maximum speed of rotation, in the manner hereinafter described, under the power of the spring 22, such dog will be freed from the notch 27 and centrifugally held entirely away from the hub 21, 20 until the carriage slows down toward the end of its rotation, and in this manner frictional drag of the dog upon the hub is substantially eliminated. D designates locking and releasing means for the sleeve 12 and 25 its flange 12^a, the same preferably comprising a cam head 28 pivoted to the base 16, as at 29, and having a preferably serrated periphery 30 adapted to impinge upon the periphery of the flange 12^a, the material of 30 such cam head 28 being preferably harder than the material of such flange, so as to cause an efficient binding engagement for the purpose of locking the flange and the sleeve 12 against rotation. The cam head 28 is provided with a lever arm 31, at the other 35 side of the fulcrum 29 whereby such cam head may be manipulated, either to lock the flange 12^a against rotation or to free it for rotation, under the urging of the energy 40 stored in the spring 22. To return to the arms 8 and 9, the counter-weight or counterpoise 10 is provided with a transverse bore whereby it may receive and be adjusted lengthwise of the arm 9, and fixed in position of adjustment by means of a thumb screw 32. The crucible A comprises a casing 33 closed at its bottom and at one side, 45 open at its top and at one end, and provided with a lateral opening 33^a at one side. One end, 33^b, is partially closed, but provided with the opening 6, heretofore mentioned, and it is adapted to communicate with the open end of the flask B, so that the fused metal may be centrifugally driven from the 50 crucible through such opening 6 into the mold b in the investment c in the flask. Within the casing 33, and resting upon the base thereof, is a carbon block 34, provided with a top recess 35, and upon which is disposed the metallic mass to be fused and directed centrifugally to the mold in the flask. Within the casing 33, and at the closed side and closed bottom thereof and arching somewhat over the central portion of the 55 interior of the casing and extending to the top

of the casing is a heat-insulating medium or member 36, such as asbestos, mineral wool or magnabestos or other composition. The carbon block 34 is disposed within the zone of the lower portion of this heat insulating material. The casing 33 is provided with a downward extension 33^c which is bored to receive the arm 8, so that the crucible A and its adjunct the flask B may be adjusted lengthwise of such arm 8, and held in position of adjustment by a thumb screw 37. 75

The means C for holding the flask to the crucible, in addition to the flange 7 upon the flask, comprise a disk or head 38 which is adapted to abut against the closed outer end of the flask, such disk or head being mounted at one edge or side upon a rod 39 which passes adjustably through a perforated lug 40 formed or provided at the closed side of the casing 33, there being a thumb screw 41 threaded in the lug 40, and adapted to impinge upon such rod 39 to hold it in position of its adjustment jointly with the disk 38. 80

Any suitable means may be employed for 90 supplying heat within the crucible casing to fuse the metal mass therein, prior to its centrifugal ejection to the mold b. To that end I have disclosed in the drawing electrical means comprising an electrical path 95 including circuit wires e and f controlled as to energization by a switch g, such path likewise including the base 16 and the metallic members mounted therein and thereupon, likewise including the arm 8 and the metallic casing 33 of the crucible, electrical resistance being included within such path. A metallic terminal h is connected with one 100 end of the circuit wire f, and may be brought into electrical contact with the carbon block 105 34 to complete a circuit and transform the electrical energy into heat for raising the temperature of such block and the mass to be fused. It will be understood of course, that a blow-pipe or any other means of 110 producing intense heat or supporting intense combustion, may be utilized, and its heat units introduced within the casing of the crucible at the open side 33^a thereof, the heat insulating medium 36 preventing dissipation of such heat units and their concentration upon the metal to be fused. 115

The operation, method of use and advantages of the improvements under treatment will be readily understood from the 120 foregoing description, taken in connection with the accompanying drawing and the following statement:

The flask B is connected with the crucible A by the flange 7 and the holding means C, and both of such elements A and B, together with the mass of metal to be fused in the crucible, are properly adjusted upon the arm 8, in conjunction with a suitable adjustment of the counterpoise 10, so that a 125 130

- proper balanced condition of the rotating elements is produced, both with respect to centrifugal and gyrostatic influences. This is of high importance, and is preëminently 5 provided for in accordance with the present invention, so that a minimum of frictional loss will accompany the rotation of the parts, and conservation of a maximum of the energy of the spring 22 will result. Us- 10 ing the counterpoise 10 as a crank, the arm 9 will cause the rotating parts to be set into motion and the dog 25 will cause the hub 21 to rotate, the rotation being produced contra-clockwise. Thus the spring 22 will be 15 put under compression and its energy stored for use in rotating the parts in a clockwise direction when desired. After the spring has been so compressed the locking and re- 20 leasing means D is rendered effective by bringing the cam head 28 into impingement with the flange 12^a, as shown in the drawing, and the rotating parts remain at rest until such cam head is voluntarily operated to 25 release the rotating parts. Prior to such release, the metallic mass in the crucible is subjected to intense heat, either by the electrical devices shown in the drawing, or by a blow-pipe or other medium or agency, and during such heating treatment the flask with 30 its mold are insulated from the crucible, which may be done by introducing a sheet of asbestos or like material across the opening 6 in one end of the crucible. When the metal has been fused in the crucible, 35 such sheet shown at 6^a, is removed, it having effectively insulated the investment within which the mold is formed and thus pre- 40 vented any impairment of the mold by heat action. Thereupon the cam head 28 is with- 45 drawn from the flange 12^a, and the spring 22 sets the rotating parts in motion clock- 50 wise, in perfect balanced condition, and supported by the point bearing 18, a pro- 55 nounced centrifugal effect being produced upon the fused metal in the crucible, and the same being thus ejected from the crucible into the mold b in the flask, and under such centrifugal pressure effectively and accurately and completely filling the mold and 60 producing a casting of exact dimensions and perfect conformation. After the mold has thus been filled, the rotation continues for an appreciable period, which may be pre- 65 determined, and thus the centrifugal action 70 presses the fused metal into every angle and recess in the walls of the mold, thus pre- 75 venting any globular metallic formation and producing a perfect consolidation of the metal in exact complement to the mold. 80
- 60 The insulating medium 36 effectively con- 85 fines the heat to the working zone in which the metal is disposed, and prevents dissipation of heat therefrom.
- In accordance with the present invention 90 I am enabled to produce a perfect casting
- in a mold unimpaired by any preliminary exposure to intense heat, and the resultant casting, whether it be for purposes of dentistry or jewelry or others of the fine arts, will in all respects be accurate and perfect 70 and perfectly match and fit the tooth, mounting or other part or device or element with which it is to be associated.
- It is manifest that many changes and variations, with respect to the specific disclosure of the drawing and of the foregoing description and statement, may be made, in practising the invention, and in adapting the invention to varying conditions of use and service, all without departing from the 80 true spirit of the invention, and a proper and fair interpretation thereof.
- Having thus disclosed my invention, I claim and desire to secure by Letters Patent:
1. Improvements of the character disclosed, comprising a crucible, a mold applied to the crucible, means for fusing metal in the crucible, removable means separating the mold from the crucible during such fusing process, and means for subjecting the crucible and mold to centrifugal action. 85
  2. Improvements of the character disclosed, comprising a crucible, a mold applied to the crucible, means for fusing metal in the crucible, a removable gate member sep- 95 arating the mold from the crucible during such fusing process, and means for subjecting the crucible and mold to centrifugal action. 95
  3. Improvements of the character disclosed, comprising a crucible, a mold applied to and carried by the crucible, means for fusing metal in the crucible, a removable gate member slidably inserted between the mold and crucible during such fusing process, and 100 means for subjecting the crucible and mold to centrifugal action. 105
  4. In improvements of the character disclosed, a crucible comprising a casing hav- 110 ing an opening at one end thereof, a flask for a casting mold fitted against the said end of the crucible casing, positioning means upon the crucible casing for engaging the inner end of the flask, a slide adjustably mounted upon the crucible casing, and 115 clamping means carried by the slide for engaging the outer end of the flask. 115
  5. In improvements of the character disclosed, a crucible comprising a casing hav- 120 ing an opening in one end thereof, a position- 125 ing flange surrounding the opening, a flask for a casting mold having the inner end thereof detachably engaged by the flange, a slide adjustably mounted upon the crucible casing, and a clamping head pro- 130 jecting laterally from the slide and engag- 130 ing the rear end of the flask to hold it in position. 130
  6. In improvements of the character disclosed, a crucible comprising a casing hav-

ing an opening at one end surrounded by a flange, a flask for a casting mold adapted to be fitted within said flange and against said end of said casing, and means further 5 for holding the flask to the casing and adjustably mounted in connection with the casing.

7. In improvements of the character disclosed, a crucible comprising a casing having an opening at one end surrounded by a flange, a flask for a casting mold adapted to be fitted within said flange and against said end of said casing, and means further for holding the flask to the casing and adjustably mounted in connection with the casing; 10 15

said last named means comprising a part adapted to abut against the outer end of the flask, a lug upon the casing, and a rod upon which said part is mounted and which is adjustable through an opening in said 20 lug, means being provided for holding said rod in position of adjustment.

In testimony whereof I have signed my name to this specification in the presence of two subscribing witnesses.

GEORGE M. HOLLENBACK.
